UNITED STATES PATENT OFFICE

167,906

AUTOMOBILE

Georges H. Muller, Poissy, France

Application October 5, 1950, Serial No. 12,460

Term of patent 3½ years

(Cl. D14—3)

To all whom it may concern:

Be it known that I, Georges Henri Muller, a citizen of the French Republic, residing at Poissy, Department of Seine & Oise, France, have invented a new, original, and ornamental Design for an Automobile, of which the following is a specification, reference being had to the accompanying drawings, forming part thereof.

In said drawings:

Fig. 1 is a side elevation of an automobile, showing my new design.

Fig. 2 is a plan view of the same.

Fig. 3 is a front view of the same.

Fig. 4 is a rear view of the same.

Fig. 5 is a front perspective view of the same taken at a 45° angle.

Fig. 6 is a smaller rear perspective view of the same.

I claim:

The ornamental design for an automobile, as shown.

GEORGES H. MULLER.
